POINT FORMING MECHANISM

Herbert A. Corbett, Auburn, N. Y., assignor, by
mesne assignments, to Auburn Fishhook Com-
pany, Inc., Auburn, N. Y., a corporation of New
York

Application October 20, 1949, Serial No. 122,528

2 Claims. (Cl. 78—23)

1

This invention relates to point forming mechanism, and is herein illustrated as embodied in a machine for swaging points on fishhook blanks.

In pointing fishhook blanks on machine commonly employed for the purpose is a rotary swaging machine in which a plurality of rotating dies are caused to deliver a succession of blows to the end portions of a blank advanced between the dies progressively reducing the material of the blank to shape it into a point. The rapidity with which the swaging operation can be performed is largely determined by the number of blows which the dies can deliver as the blank is advanced between them. Thus if the number of blows delivered per minute can be increased the speed of advance movement of the blank can likewise be increased, and, accordingly, the time required for the operation will be reduced.

In view of the foregoing, it is an object of the present invention to provide an improved point forming machine which will be effective to form points of uniform character on blanks, and which at the same time will be particularly rapid in its operation.

To this end, and as shown, the invention provides in a machine of the type referred to, a rotary head carrying a pair of dies having cooperating tapered blank engaging grooves, and fingers pivoted on the head for operatively engaging the dies, together with pneumatic means for actuating the fingers to cause the dies to deliver a series of blows to a blank during rotation of the head.

Preferably, and as illustrated, the pneumatic means is an air hammer having a plunger arranged to engage balls carried at the inner ends of the fingers. The air hammer can be operated at a high speed causing a rapid succession of blows to be delivered to a blank by the dies. Furthermore, the arrangement of pivoted fingers operated by the plunger through balls at the ends of the fingers provide a comparatively simple construction for actuating the dies and one which friction and consequent wear of the parts is reduced to a minimum.

These and other features of the invention are disclosed in the following specification and in the accompanying drawings, and are pointed out in the claims.

In the drawings,

Fig. 1 is a side elevation, partly in section, of a swaging machine, embodying one form of the invention;

Fig. 2 is an end view, partly in section of the machine;

2

Fig. 3 is a side view of a fishhook blank to be operated upon; and

Fig. 4 is a side view of a fishhook blank having a point formed by the machine.

The machine is adapted for operation upon fishhook blanks such as blank 10, Fig. 3, one end of which has been slabbed off as indicated by reference character 12, and operates upon such a blank to form a conical point 14, Fig. 4. To this end, the blank 10 is held in a chuck 16, in horizontal position, with its partially formed point extending inwardly toward a rotary swaging head 18 carrying dies 20, which are moved with the head, toward and away from the blank during a point forming operation.

The head 18 is a hollow casting carrying a bushing 22 rotatably mounted in a bearing 24 at one end of a base block 26. The bushing 22 has secured to it, by screws 28, a face plate 30 which in turn is secured to the head 18 by screws 32, Fig. 2. The head is rotated by means of an electric motor 34 having a pulley 36 carrying a drive belt 38 positioned in a groove 40 in the inner end of the head.

Each of the dies 20 is rectangular in shape and has a tapered blank engaging groove 42 in one face thereof, such that, when the dies are in cooperative relation, the grooves together form an elongated conical recess approximating the shape of a point to be formed upon a blank.

The dies are slidably mounted in a slot 44, Fig. 2, formed between walls of wear plates 46, secured by screws 47 to the forward portion of the head. The dies are held against movement axially of the head by a hardened backing plate 48 and by the face plate 30. The face plate has a central opening in which is inserted a nipple 50 which serves to guide the blank to the dies and partially to support the blank during operation upon it.

Means for causing the dies to deliver blows to the blank as the head is rotated comprises a pair of fingers 52 pivoted on pins 54 mounted in the head. The fingers have forwardly projecting nose portions 56 adapted to engage buffer blocks 58 mounted in openings 60, Fig. 2, between the wear plates above and below the dies 20.

The inner end of each finger 52 is provided with a recess 62 within which is positioned a ball 64. The balls together form a bearing for a conical head 66 of a bit or plunger 68 of a pneumatic or air hammer indicated generally by reference character 70. The air hammer, which may be of any suitable commercial construction, as herein shown, comprises a hollow casing 72, mounted in a recess 74 in the block 26, and hav-

ing at its forward portion a sleeve 76 for receiving the bit 68 and having positioned within its rearward portion a reciprocating piston 78, the casing being provided with the usual air inlet opening 80 and exhaust ports 82.

Operation of the air hammer intermittently forces the bit 68 against the balls 64 causing the inner ends of the fingers 52 to separate and the nose portions 56 to press sharply upon the buffer blocks 58 causing the dies 20 to deliver a series of blows to a blank presented to the dies.

Vibration of the air hammer is reduced by backing the casing 72 with a buffer plate of sponge rubber 84 held in position in the recess 14 and a bearing plate 86, adjustably positioned by a set screw 88 extending through a cap 90 secured to the base block 26 by screws 92.

Preferably, the block 26 is mounted upon a bracket 94 secured by bolts 96 to a dove-tail slide 98 positioned in ways 100 in the machine frame 102. The slide 98 and its associated parts are reciprocated in the ways, in directions toward and away from the chuck 16 by means of a suitable cam 104 engaging a roll 106 carried by an arm 108 on the inner end of the slide 98.

It is contemplated that a series of chucks 16 mounted upon a chain conveyor 110 supported on the frame 102 be advanced intermittently by any suitable means, not shown, past the swaging head successively positioning in alignment with the head the blanks to be pointed.

In the operation of the machine, the head 18 is rotated at about 600 revolutions per minute and the air hammer 70 is actuated at about 13,000 cycles per minute. After a blank 10 in a chuck 16 is located in alignment with the grooves 42 of the dies 20, the head and its associated parts are moved, under the control of the cam 104, toward and away from the chuck. As the dies pass over the slabbed end of the blank the air hammer, 40 acting through the bit 68, balls 64, and fingers 52, causes the buffer blocks 58 to force the dies toward each other under high pressure, delivering blows in rapid succession to the end of the blank as the dies are moved progressively along the blank and rotating around it. This operation causes a flow of material of the end portion

of the blank progressively tapering it to conform to the shape of the grooves 42 and produces a conical point 14, Fig. 4.

Having thus described my invention, what I 5 claim as new and desire to secure by Letters Patent of the United States is:

1. Point forming mechanism comprising a frame, means upon the frame for supporting a blank to be operated upon, a slide mounted upon the frame for movement toward and away from the supporting means, an air hammer carried by the slide, a head mounted for rotation in the slide, a pair of dies slidably mounted in the head, the dies having cooperating tapered blank engaging grooves, a pair of fingers pivoted upon the head and located upon opposite sides of the dies in position to grip the same, means operatively connecting the fingers with the hammer for actuating the fingers, means for rotating the head, and means for reciprocating the slide.

2. Point forming mechanism comprising a frame, means on the frame for supporting a blank in horizontal position, a slide carried by the frame, a head rotatably mounted on the slide, cooperating swaging dies slidably mounted in the head, fingers pivotally mounted upon the head and having outer end portions in operative engagement with the dies, an air hammer mounted upon the slide, said fingers having inner end portions in operative engagement with the air hammer, means for rotating the head, and means for moving the slide toward and away from the blank supporting means.

HERBERT A. CORBETT.
